CONTROL MECHANISM

Nicholas Pelosi, Newark, N. J., assignor to American Can Company, New York, N. Y., a corporation of New Jersey

Application December 30, 1937, Serial No. 182,637

7 Claims. (Cl. 192—127)

The present invention relates to a machine control mechanism and has particular reference to detecting adverse conditions in an advancing web of material to the end that the web may be 5 without imperfections and in proper position for use.

In the manufacture of various articles, including containers or cans made from fibrous material it has been found expedient to produce such articles from a continuous web of material which 10 may be supplied from a roll or the like. The web is preferably fed into a machine which partially or wholly produces the article. The web, in being fed, sometimes breaks and this may produce 15 a tangle which aside from loss of stock may also damage the machine. Also the web may contain an opening such as a hole or other imperfection which if allowed to go through the machine will result in imperfect and damaged work. At other 20 times the web in being fed into the machine may shift or run off at an angle or its travel may be uneven, irregular or erratic. Such travel is commonly known as "weaving", and this again will result in imperfect work.

25 The present invention contemplates the detection of adverse conditions of an advancing web which includes anything not properly found in the web at a given time and when such a condition is detected provision is made for preventing 30 the condition doing damage.

Such difficulties may be of improper feeding, of improper position, or of torn or imperfect surface or other property in the web of fibrous material and when so detected feeding of the web 35 is terminated until a break is repaired, or the portion of the web containing a hole is removed, or until the web is realigned to prevent its "weaving".

An object, therefore, of the invention is the 40 provision, for a moving web of fibrous material or the like, of electric detecting and machine line control mechanism which will detect breaks and holes in the moving web and which, at the same time, will prevent "weaving" of the web so 45 that the undesirable effects of such difficulties will be prevented.

Numerous other objects and advantages of the 50 invention will be apparent as it is better understood from the following description, which, taken in connection with the accompanying drawing, discloses a preferred embodiment thereof.

Referring to the drawing: 55 Figure 1 is a schematic perspective view of a web feeding apparatus including detecting mechanism embodying the instant invention and show-

ing a web being fed along a predetermined path of travel from a supply roll, parts being broken away, the view also including a wiring diagram which is associated with the detecting mechanism;

Fig. 2 is an enlarged fragmentary top plan view of a portion of the feeding apparatus and of the detecting mechanism; and

Fig. 3 is a sectional view taken longitudinally of the travel of the web, this being substantially 10 along the broken line 3—3 in Fig. 2.

As a preferred embodiment of the instant invention the drawing illustrates a web of fibrous material A being advanced from a supply roll B through a feeding apparatus C, which includes 15 a web detecting and control mechanism D. The web of fibrous material may be paper or the like from which containers or other fibrous articles of manufacture are produced.

The supply roll B of the fibrous material is 20 preferably supported in a horizontal position on a shaft 11 (Fig. 1) carried in bearings 12 formed in a pair of sub-frames 13. Web A is threaded through the feeding apparatus C preferably passing under an idler roller 15 then over a metal 25 detector roller 16 and hence between a pair of feed rollers 17. These rollers are mounted on shafts journaled in suitable bearings formed in a main frame 18.

The feed rollers 17 are rotated in unison by 30 any suitable means such as an electric motor 19. For this purpose one of the shafts of the feed rollers 17 is provided with a pulley 21 which is driven by an endless belt 22 taking over a drive pulley 23 on the shaft of the motor 19. Rotation 35 of the feed rollers 17 by the motor thus draws the web A through the apparatus as it unrolls from the roll B and also advances it to any suitable machine for further treatment.

The detector and control mechanism D is located adjacent the detector roller 16. This mechanism preferably includes a fine bristle, copper wire, brush 31 which is clamped between a metal top plate 32 and a bottom plate 33. The top plate 32 extends the full length and width of the 45 brush and the bottom plate 33 also extends the full length of the brush but only sufficient of its width to hold the brush in place.

The top plate 32 is protected by an overlying insulating plate 34 which is secured in place by 50 screws 35. A clip or finger 36 is secured by a pivot screw 37 to each end of the top plate 32. These two clips rest of their own weight on the extreme edges of the web A as shown in Fig. 2 as the web moves over the detector roller 16.

The brush unit just described is supported in a substantially horizontal position on a pivot rod 38 which is disposed in a bearing 39 formed in the bottom plate 33. The ends of the pivot rod 38 are carried in bearings 41 which are formed in the main frame 18. The brush 31 normally rests on top of the web A as the latter passes over the detector roller 16 but may be swung out of the way when desired by lifting the free end of and 10 by rotating the brush unit on the pivot rod 38. When in non-operating position the brush unit may be supported on an L-shaped pin 42 which is secured in the main frame 18. The pin extends through a hole 43 in the insulating plate 15 34 and contacts directly with the metal top plate 32 of the unit.

The brush unit controls the operation of the electric motor 19. This is effected by electric apparatus including a detector electric circuit 20 and a motor circuit which are shown in the wiring diagram in Fig. 1 and which are interposed between the brush unit and the motor.

The detector circuit includes a wire 51 one end of which is connected to a terminal 52 which is 25 secured in the top plate 32 of the brush unit. The other end of the wire 51 is connected to a source of electric energy such as, for example, a generator 53. The generator is also connected by a wire 55 to a solenoid 56 which is part of a 30 relay switch 57. The solenoid in turn is connected by a wire 58 to a spring brush 59 which is secured to the main frame 18 end which is held in frictional contact with the metal detector roller 16. The circuit is thus grounded on the 35 machine frame 18.

The motor circuit includes the relay switch 57 and comprises besides this switch, a pair of switch terminals 61, 62 which are normally engaged by the switch points. The switch is thus normally 40 closed. Terminal 61 is connected by a wire 63 to the motor 19. Terminal 62 is connected by a wire 64 to a source of electric energy such as an auxiliary generator 65. The auxiliary generator is also connected by a wire 66 to the motor. 45 When the motor circuit is closed this being under normal operating conditions, as, when the relay switch is closed, electrical energy flows from the auxiliary generator 65 to the motor 19. Operation of the motor, as hereinbefore explained, 50 rotates the feeding rollers 17 and this feeds the web A of material through the apparatus.

When there is a break or a hole (indicated in Fig. 1 by the letter H) in the moving web A this is detected as it passes over the detector roller 55 16. At that time more or less of the bristles of the brush 31 extend through the break or the hole and directly contact the detector roller 16. This contact immediately establishes and closes the detector circuit and electric energy from the 60 generator 53 energizes the solenoid 56.

When the solenoid is energized its sliding core 65 opens the relay switch 57 and thereby breaks the motor circuit at the contacts 61 and 62. Thus the motor stops operating and feeding of the web A is terminated. Not until the break in the web is repaired or the portion of the web containing the hole is cut out and the web again pieced together to provide a continuous surface 70 can the motor be again started.

When "weaving" of the web A causes one of the clips 36 to ride off the edge of the web A it contacts the detector roller 16. This establishes the detector circuit, in the same manner as just explained for a break or a hole in the web, and

the solenoid 56 being energized the motor circuit is broken and stopping of the motor results.

When the web has been realigned on the roller and the clips replaced on top of the web the detector circuit will be broken at the web. The web A serves as insulation on the detector roller 16 as long as the clips 36 or the brush 31 remain on the web and are held away from and out of contact with the roller. The motor circuit can then be re-established so that feeding of the web 10 will be resumed.

Provision is also made for preventing normal feeding of the web A when the brush unit is in non-operating position as when laid back on the L-shaped pin 42. When in this position the pin 15 42 directly contacts the top plate 32 of the brush unit and this completes the detector circuit between brush and detector roller through the medium of the main frame 18. Establishment of the detector circuit in this manner accomplishes 20 the same result as when completed during "weaving" or breaking of the web.

It is thought that the invention and many of its attendant advantages will be understood from the foregoing description, and it will be apparent 25 that various changes may be made in the form, construction and arrangement of the parts without departing from the spirit and scope of the invention or sacrificing all of its material advantages, the form hereinbefore described being 30 merely a preferred embodiment thereof.

I claim:

1. A control mechanism for a machine operating on a web of insulating material fed therethrough, comprising in combination: feeding means including an electric motor for advancing the web through the machine, a metal detector roller over which said web passes, a flexible metallic brush pivotally mounted above said metal roller and normally held separated and insulated 40 therefrom by said web, said metallic brush being adapted to make electrical connection with said detector roller when an opening in said web breaks the insulation by allowing engagement between brush and roller, such electric connection 45 stopping said motor and travel of said web.

2. A control mechanism for a machine operating on a web of material as it is fed therethrough, comprising in combination: feeding means including an electric motor for advancing the web through the machine, a metal detector roller over which said web passes, a flexible brush member pivotally mounted above said detector roller and normally held separated therefrom by 50 said web, said brush member substantially extending across the entire width of said web, an electric motor circuit for said motor, a normally open electric detector circuit including said detector roller and said brush member, and a relay switch common to both circuits and normally holding said motor circuit closed, said flexible brush member closing the detector circuit and energizing said relay switch to break the motor circuit and stop feeding of the web when an imperfection in the web passes over 55 the roller and allows said brush member to contact the detector roller.

3. A control mechanism for a machine operating on a web of material fed therethrough, comprising in combination, feeding means including a detector roller for advancing the web through the machine, and detector devices electrically connected with said web feeding means, said detector devices including a pivotally mounted flexible metallic brush member nor- 70

5 mally maintained by said web out of contact with said roller, said member operating to contact said roller to stop actuation of said web feeding means when said devices detect imperfection of condition of the web of material and its position on and relative to said roller.

10 4. A control mechanism for a machine operating on a web of material fed therethrough, comprising in combination, feeding means including a detector roller for advancing the web through the machine, and detector devices electrically connected with said web feeding means and adaptable to press against said web during normal feeding thereof but being movable into detecting position when not properly held by said web, said detector devices including independent pivotally mounted flexible metallic brush members normally maintained by said web out of contact with said roller, said members operating 15 to contact said roller and energize an electric circuit to stop said web feeding means when said web is defective or out of position relative to said detector roller.

20 5. A control mechanism for a machine operating on a web of material being fed therethrough, comprising in combination feeding means including an electric motor for advancing the web through the machine, electric detector devices including a detector roller arranged as a part of an electrical circuit and disposed adjacent the path of travel of said web, said detector devices further including a pivotally mounted flexible metallic brush member movable into and out of detecting position, said brush member being movable by gravity into detecting position against said roller when continuity of the web is interrupted, and operating through said electrical circuit to stop actuation of said motor, a supporting unit arranged to support said brush member out of operating position, and an additional electrical circuit connecting said detector devices and said supporting unit with said motor, said supporting unit operating through

said last mentioned electrical circuit to stop actuation of said motor when said brush member is in non-operating position on said supporting unit.

6. A control mechanism for a machine operating on a web of material fed therethrough, comprising in combination feeding means including an electric motor for advancing the web through the machine, a metal detector roller over which said web passes, a finger and a flexible metallic brush member pivotally mounted above and adjacent each longitudinal edge of the web where it passes over said roller, said fingers being normally separated from the roller by engaging on the moving web, and electric circuits connecting said fingers with said electric motor, said fingers and said brush member operating through said electric circuits to stop said feeding means upon engaging said roller when the web "weaves" on the roller and moves out of separating position.

25 7. A control mechanism for a machine operating on a web of material as it is fed therethrough, comprising in combination: feeding means for advancing the web through the machine, a metal detector roller over which said web of material is fed by said feeding means, a detector element including a flexible metallic brush member pivotally mounted above said roller and normally held separated therefrom by said web, a finger pivotally mounted above and adjacent each marginal edge of the web where it passes over said roller, said fingers being normally held separated from the roller by the edges of said web, said detector element and a said finger being engageable respectively with said metal 30 roller to electrically interrupt said feeding means to stop the advancement of said web when an imperfection in the web registers with said brush member and when weaving and irregular travel of the web on said roller permits contact between a said finger and said roller.

NICHOLAS PELOSI.
